Primary Examiner — David G Muller

(57) **CLAIM**

The ornamental design for a medical emesis basin being convertible to a medical tool holder combination, and having a recessed cavity on the bottom surface when in the second position. And the basin having an extended hand held handle and the emesis basin having a left and right side mouth and chin cutouts, as show and described.

DESCRIPTION

FIG. 1 is a perspective view of the medical emesis basin being convertible to a medical tool holder combination, showing my new design.

FIG. 2 is a front view thereof;

FIG. 3 is a rear view thereof; with the extended handle;

FIG. 4 is a right view thereof;

FIG. 5 is a left view thereof;

FIG. 6. is a top view thereof; with the right and left mouth and chin cutouts.

FIG. 7 is a bottom perspective view thereof; the medical emesis basin being convertible to a medical tool holder combination position having a recessed cavity on the bottom surface for the medical tool holder.
